UNITED STATES PATENT OFFICE.

LIVERAS A. LEE, OF NATIONAL SOLDIERS HOME, TENNESSEE.

ENVELOP.

1,185,513.

Specification of Letters Patent.

Patented May 30, 1916.

Application filed December 18, 1915. Serial No. 67,58.

To all whom it may concern:

Be it known that I, LIVERAS A. LEE, a citizen of the United States, and a resident of National Soldiers Home, Washington county, Tennessee, have invented an Improvement in Envelops, of which the following is a specification.

This invention is an improvement in receptacles and has particular reference to a closure for unsealed envelopes.

An object of the invention is the provision of an elongated closure adapted to be folded intermediate its ends and inserted into the opening in the envelop with the extremity of the closure projecting slightly beyond said opening whereby it may be grasped and the closure withdrawn when it is desired to remove the contents of said envelop.

Another object is to provide the closure with a reinforcing element in order to facilitate the insertion of the closure into the envelop opening and also prevent the contents of the envelop from forcing said closure outwardly.

A further object is to provide an envelop of this character which is simple in construction, easy to manufacture, and effective in carrying out the purpose for which it is designed.

The inventive idea involved is capable of receiving a variety of mechanical expressions, one of which, for the purpose of illustrating the invention, is shown in the accompanying drawing, in which—

Figure 1 is a plan view of the envelop in closed position. Fig. 2 is a vertical longitudinal sectional view thereof. Fig. 3 is a plan view of the envelop opened. Fig. 4 is a fragmentary sectional view showing the closure in position as the same is being withdrawn from the envelop opening.

Referring more particularly to the accompanying drawing in which like reference characters indicate similar parts, the numeral 5 indicates the body of an envelop of ordinary construction having the opening 6 at one end thereof.

The closure, which comprises the essential feature of the invention, is preferably made of substantially trapezoidal formation having its longitudinal edges 7 converging out-

wardly as best illustrated in Fig. 3. Medially of the ends of the closure the same is provided with a transverse folding line 8 so that when the closure or flap is in closing position within the envelop body the same will be folded upon itself as illustrated in Fig. 2. It is to be understood that when inserting the closure into the envelop the inner portion 9 of said closure is first bent upon itself and the closure also bent along the folding line 8 so that that portion of the closure adjacent said folding line will be the first to enter the opening of said envelop. It will thus be observed that this portion of the closure which first enters the opening 6 is of less width than said opening this permitting of the easy insertion of the closure into the envelop without the edges 7 thereof binding against the longitudinal edges of the body portion. In order to further facilitate the insertion of the closure or flap into the envelop body and prevent the contents of the latter from inadvertently forcing said closure outwardly the latter is preferably provided upon its outermost portion 10 with a longitudinally extending reinforcing or stiffening element 11 in the form of a strip of card board. This element 11 at all times retains the portion 10 of the closure straight and also causes said portion to be forced against the adjacent inner face of the envelop as shown in Fig. 2.

The outer portion 10 of the closure is preferably of slightly greater length than the inner portion 9 so that when the same is in closing position as shown in Fig. 2 the extremity of the outer portion 10 will project slightly beyond the opening 6 so that said extremity may be grasped and pulled outwardly when it is desired to open the envelop and remove the contents thereof.

What is claimed is:

An envelop comprising a body portion including a front and back and having one open end, a closure for said open end of substantially the same length as the body portion and of trapezoidal formation, said closure having a transverse folding line dividing the same into outer and inner portions, the former of which is of slightly greater length than the latter whereby the free end

of the closure will project beyond the open end of the envelop when the closure is in closing position, and an elongated reinforcing strip secured longitudinally and centrally of the outer portion of the closure and terminating adjacent the outer extremity of said portion and said folding line, said reinforcing strip engaging the inner face of the back of the envelop when the closure is in closing position.

LIVERAS A. LEE.
